UNITED STATES PATENT OFFICE.

HUBERT F. KRANTZ, OF BROOKLYN, NEW YORK, ASSIGNOR TO KRANTZ MANUFACTURING COMPANY, INC., OF BROOKLYN, NEW YORK, A CORPORATION OF NEW YORK.

SWITCHBOARD.

1,305,374.

Specification of Letters Patent. Patented June 3, 1919.

Application filed May 19, 1913. Serial No. 768,415.

To all whom it may concern:

Be it known that I, HUBERT F. KRANTZ, a citizen of the United States, residing at Brooklyn, in the county of Kings, city and State of New York, have invented certain new and useful Improvements in Switchboards, of which the following is a clear, full, and exact description.

This invention relates to an improved switchboard for electrical circuits of the same generic construction as that shown in my application for United States Patent Serial Number 651,565, filed September 27th, 1911; that is, it comprises a board in which the switch contacts may be made directly upon the bus bars intermediate the ends of the bus bars, whereby the use of cross bars may be eliminated.

One object of this invention is to so arrange the parts as to permit the ribbon-like bands which constitute the bus bars to be placed on edge on the back board to get a greater insulated air space between the bars with a less width of board between the bars.

A further object is to permit the carrying of the branch circuit connections, fuses and branch circuit side of the switch contacts on the side of the board away from the operator to make what may be called a "dead-face board," and at the same time to save vertical height of such board, which is a great desideratum in modern work.

In carrying out the first object of the invention, to wit: the carrying of the bus bars on edge, I generally run these bus bars vertically up and down the back of the board, one bus bar parallel to the next, although of course, they may be run horizontally if desired.

In carrying out the second object of the invention, I generally mount the branch circuit connections, fuses and switch terminal on supports or shelves in the rear of the back plate connected by suitable brackets with the back plate, and these supports or shelves in my preferred construction are in a plane at right angles to the back board itself. The shelf support for fuses, branch circuit connections and switch contacts may also carry the cables for the branch circuit connections beneath the shelf. There may be any number of such shelves located one above the other on the back plate.

The switch may be mounted on switch brackets so that the two blades, where there

are two blades, may contact one with the bus bar direct and one with the switch contact for the branch circuit, or the switch may be mounted on either the bus bar or branch circuit contact and swung in and out of its circuit-closing position. In either instance the switch lever may be mounted on the face of the board and a connecting rod run through the board to operate the switch. Any suitable type of switch or operating lever, therefore, may be used, such as pull, push, quick-break or slow-break.

The scope of my invention will be pointed out in the claims.

In the accompanying drawings, wherein are shown one or more of various possible embodiments of the several features of the invention,

Figure 1 is the section on the line 1—1, Fig. 4, of a portion of a switch-board constructed in accordance with this invention.

Fig. 2 is a sectional view on the line 2—2, Fig. 4, showing an arrangement of one switch vertically above another.

Fig. 3 is a section on the line 3—3, Fig. 1. 80

Fig. 4 is a rear elevation of a switch-board with four switches in place.

Fig. 5 is a sectional view similar to Fig. 2, of a modified form of switch.

Referring now more particularly to Fig. 1 of the drawings, there is shown at 1 a back plate, generally of marble or slate, and at 2 a suitable number of brackets bolted to the back plate and carrying the supporting shelves 3, preferably of slate; the brackets 4 carry the shaft 5 for operating the switch blades 6, which are arranged in pairs and insulated from the shaft 5, as shown by Fig. 3, by a collar of insulation 7. The bus bars 8, 9, and 10 are secured, parallel to each other, to the back of the board by angle brackets 11. It will be noted that they are fastened in place edgewise, and as shown in Fig. 1, form thus a contact for the switches 6. The shaft 5 may be connected by a connecting rod 12 with the operating lever 13 pivoted at 14 to a bracket 15 at the face of the board, the rod 12 passing through an opening 16 in the board.

As shown in Fig. 5, the switch blade 18 may be pivoted at 17 to a bus bar 8 in which instance the connecting rod 12 will be attached at a point 20 to an insulated block 21, mounted on the switch blade 18.

The supporting shelves 3 each carry in 110

line with the bus bar or switch blade switch contacts 22 secured to the fuse terminal 23, which in turn is joined by the fuse 24 with the fuse terminal 25 carried on the branch circuit connection block 26 where the set screw 27, or similar device, used to attach one end of a branch circuit wire 28 coming from a branch circuit cable 29. The branch circuit cables may be secured beneath each supporting shelf and distributed from a central point such as shown in Fig. 4 toward the ceiling of the switch board room and thus run out in the conduits of the building. It will be apparent from the examination of the drawings that the only conductors of any description which pass or cross the bus bars are the insulated branch circuit cables and they pass the bus bars at a goodly distance away from the bus bars on the supports. It will be noticed that cross bars are entirely done away with by the simple device of mounting the switch terminals in line with the bus bars on a separate support and causing the contact blade of the switch to operate on the bus bar and on the branch circuit terminal contact blade.

In carrying out this invention, details of construction may be varied from those shown, and yet the essence of the invention be retained; some parts might be employed without others, and new features thereof might be combined with elements old in the art in diverse ways, although the herein described type is regarded as embodying substantial improvements over such modifications.

As many changes could be made in the above construction, and many apparently widely different embodiments of the invention could be made without departing from the scope thereof, it is intended that all matter contained in the above description or shown in the accompanying drawings shall be interpreted in an illustrative and not in a limiting sense.

It is furthermore desired to be understood that the language used in the following claims is intended to cover all the generic and specific features of the invention herein described, and all statements of the scope of the invention which as a matter of language might be said to fall therebetween.

I claim as my invention:

1. Apparatus of the character described comprising, in combination, an insulating support, bus-bars mounted directly thereon, brackets secured at right angles to said insulating support and extending beyond said bus-bars, a second insulating support mounted on said brackets and extending transversely to said bus-bars, branch-circuit terminals mounted on said last mentioned support, and a switch adapted to contact with a bus-bar and a branch-circuit terminal.

2. Apparatus of the character described

comprising, in combination, an insulating support, bus-bars mounted on one face thereof, brackets secured at right angles to said insulating support and extending beyond said bus-bars, a second insulating support mounted on said brackets and extending transversely to said bus-bars, branch-circuit terminals mounted on the last mentioned support in alinement, respectively, with said bus-bars, and a switch adapted to contact with a bus-bar and a branch-circuit terminal.

3. Apparatus of the character described comprising, in combination, an insulating support, bus-bars mounted directly thereon, brackets secured at right angles to said insulating support and extending beyond said bus-bars, a second insulating support mounted on said brackets and extending transversely to said bus-bars, branch circuits disposed beneath said second insulating support, branch-circuit terminals mounted on said second insulating support, and a switch adapted to contact with a bus-bar and a branch-circuit terminal.

4. In a switchboard, a base, an elongated conductor mounted upon and parallel to said base, a stationary contact mounted at the same side of the base at a distance from said elongated conductor and in a plane perpendicular to the base and coincident with the plane of the conductor, a switch member pivotally supported intermediate its ends for operation in said plane to make electrical connection between the elongated conductor and the stationary contact, and a link-and-lever mechanism mounted upon the base for actuating the said switch member.

5. A switchboard comprising a baseboard, a plurality of shelves disposed in parallel relation and spaced apart adjacent said baseboard, an elongated conductor extending transversely to said shelves between the same and said baseboard, branch-line terminals mounted on said shelves adjacent said conductor, and switch blades pivotally supported intermediate their ends and movable to effect engagement with said conductor and with corresponding branch-line terminals.

6. A switchboard combining a baseboard; a plurality of parallel strips of insulating material spaced apart and disposed edgewise to said baseboard at a distance therefrom; a series of parallel bus-bars extending between said baseboard and said strips, transversely to the latter; branch-line terminals mounted on said strips; and switch-blades pivoted at their center points to swing into positions to establish electrical connections between their respective branch-line terminals and said bus-bars.

7. A switchboard combining a baseboard; a plurality of parallel strips of insulating material spaced apart adjacent to said baseboard; an elongated conductor extending

- transversely to said strips between the same and said baseboard; branch-line terminals mounted at the edge of said strips adjacent to said conductor; and a switch blade pivoted at a point intermediate its ends to swing into engagement with its respective branch-line terminal and the conductor. 70
8. A switchboard combining a baseboard; a narrow elongated strip of insulating material disposed adjacent to one face of said baseboard but spaced therefrom; a plurality of parallel conductors extending edgewise along the face of said baseboard between the same and said strip; a corresponding number of branch-line terminals, each arranged on said strip adjacent to its respective conductor; and a corresponding number of switch blades pivotally mounted at points intermediate their ends so as to be movable into positions to make contact directly with said conductor and its appropriate branch-line terminal. 75
9. A switchboard combining a baseboard; a plurality of parallel strips of insulating material disposed adjacent to one face thereof; a plurality of narrow elongated bus-bars disposed in edgewise relation to one face of said board and extending transversely to said strips between the same and said board; a plurality of branch-line terminals carried by said strip; and a corresponding number of switches normally disconnected from said terminals and said bus-bars and adapted to connect the same together. 80
- 35 10. A switchboard combining a plurality of elongated strips of insulating material spaced apart in parallelism; branch-line cables extending along the rear face of each strip; branch-line terminals carried by the front face of each strip and connected, across the plane thereof, to their appropriate branch-line conductors; a main bus-bar extending transversely to said strips; and switches normally disconnected from said bus-bar and said branch-line terminals for engaging the same directly. 90
11. A switchboard combining a baseboard; a plurality of parallel strips of insulating material disposed at an angle to said baseboard; a plurality of parallel bus-bars extending transversely to said strips between the same and said baseboard; a plurality of branch-line terminals arranged adjacent to corresponding edges of said strips in proximity to said bus-bars; and switch blades pivoted at points intermediate their ends to establish connections between said terminals and said bus-bars. 100
- 60 12. A switchboard combining a baseboard; a plurality of parallel strips of insulating material spaced apart adjacent to said baseboard; an elongated conductor extending transversely to said strips between the same and said baseboard; branch-line terminals mounted at the edges of said strips adjacent to said conductor; and a switch-blade pivoted at an intermediate point and adapted to swing to bring its one end into contact with said conductor and its other end into contact with its respective branch-line terminal. 105
13. A switch mechanism combining a common carrier mounted to swing about a center axis; a plurality of branch-line terminals arranged alongside in a line equidistant from said axis; a series of parallel bus-bars extending transversely to said axis and located on the opposite side thereof; and a multiplicity of blades mounted on said common carrier, each being adapted to establish electrical connection between its respective bus-bar and terminal. 110
14. A switchboard, consisting essentially of a vertical switchboard panel having a dead front face and a horizontal row of spaced transverse holes, brackets at the front face of, and supported by, said panel, a front shaft below said holes and carried by said brackets parallel with said front face, upright switch-operating handles in front of said holes and mounted on said shaft, brackets at the rear face of said panel, a rear shaft below said holes and parallel with said rear face and carried by said rear brackets, rockable switch blades in rear of said holes and mounted on said rear shaft, straight-blade rocking links extending through said holes and at their front ends pivotally joined to said handles and at their rear ends pivotally joined to said blades, stationary circuit-closer contacts at the rear face of said panel to coöperate with said blades, respectively, and electrical connections and bus-bars for said blades and contacts and arranged at the rear face of said panel. 115
15. In a dead-face switchboard, comprising a wall of insulating material having a transverse hole therethrough, a pair of pivot shafts disposed one at the front of the wall and the other at the rear of the wall, both being supported from said wall and being arranged substantially parallel to the respective faces of the wall and to each other, and a switch-operating handle carried by the front shaft, the combination therewith of a bus-bar supported upon the wall at the rear side thereof and adapted to carry one side of an electric circuit, a contact member also at the rear side of the wall spaced from the bus-bar and adapted to carry the opposite side of said electric circuit, a swinging switch blade of conductive material carried by the rear shaft and adapted to be swung to dispose one of its ends for making electrical connection with said contact member and for disposing its other end to complete the electrical connection with the bus-bar, and mechanical connections extending from the switch blade through said wall into engagement with the operating handle, where- 120
- 125 130

by to swing the switch blade from the operating handle at will.

16. In a dead-face switchboard, comprising a wall of insulating material having a series of transverse holes formed therethrough, a plurality of pivot shafts disposed some at the front of the wall and others at the rear of the wall, all of said shafts being supported from said wall and being arranged substantially parallel to the respective faces of the wall and to each other, and switch-operating handles carried by the front shafts, the combination therewith of a bus-bar supported upon the wall at the rear side thereof, a plurality of branch-line contact members also at the rear side of said wall and spaced from the bus-bar, a plurality of swinging switch blades of conductive material, at least one being associated with each hole in said series and each being adapted to be swung to dispose one of its ends for making electrical connection with one of said branch-line contact members while disposing its other end to complete the electric connection with the bus-bar, and mechanical connections extending from said switch blades through said holes into engagement with said operating handles, whereby to swing the switch blades from said operating handles at will.

17. A switchboard comprising a baseboard, a strip of insulating material disposed adjacent one face of the baseboard but spaced therefrom, a main conductor extending along the face of said baseboard between the same and said strip, a branch-line terminal disposed on said strip adjacent the corresponding conductor, and a switch blade pivotally mounted at a point intermediate its ends to engage directly the branch-line terminal and the main conductor.

18. In a switchboard, a base, a conductor mounted upon the said base, a stationary contact member mounted at the same side of the base at a distance from said conductor and in a plane coincident with the plane of the conductor, a switch member pivotally supported intermediate its ends for operation in said plane to make electrical connection between the conductor and the contact member, and a link-and-lever mechanism for actuating the said switch member.

Signed at Brooklyn, in the county of Kings, city and State of New York, this 16th day of May, one thousand nine hundred and thirteen.

HUBERT F. KRANTZ.
